DESIGN FOR A FIXTURE FOR HOLDING A THREAD-CUTTING TOOL OR THE LIKE WHILE GRINDING THE CUTTING END THEREOF

Harry C. Wilson, Beverly Hills, Calif., assignor to
Robert H. Clark, Los Angeles, Calif.

Application February 21, 1944, Serial No. 112,654

Term of patent 14 years

(Cl. D54—14)

To all whom it may concern:

Be it known that I, Harry C. Wilson, a citizen of the United States, residing in the city of Beverly Hills, county of Los Angeles, and State of California, have invented a new, original, and ornamental Design for a Fixture for Holding a Thread-Cutting Tool or the Like While Grinding the Cutting End Thereof, of which the following is a specification, reference being had to the accompanying drawing, forming a part thereof.

Fig. 1 is a perspective view of a tool holding fixture embodying the design of the present in-

vention, showing the under side of the fixture, one side face, and the forward end of the fixture; Fig. 2 is a rear end elevation of the fixture; Fig. 3 is a side elevation of the fixture; Fig. 4 is a top plan view of the fixture; and Fig. 5 is a bottom plan view of the fixture.

I claim:

The ornamental design for a fixture for holding a thread-cutting tool or the like while grinding the cutting end thereof, as shown and described.

HARRY C. WILSON.
